J. A. MOORE

SEGREGATING NEST

Filed April 30, 1925

Inventor:
John A. Moore
Heisler & Ramsey
Atty.

UNITED STATES PATENT OFFICE.

JOHN A. MOORE, OF PORTLAND, OREGON.

SEGREGATING NEST.

Application filed April 30, 1925. Serial No. 26,959.

To all whom it may concern:

Be it known that I, JOHN A. MOORE, a citizen of the United States, and resident of Portland, county of Multnomah, and State 5 of Oregon, have invented certain new and useful Improvements in Segregating Nests, of which the following is a specification.

My invention relates to what is commonly termed segregating nests having for 10 its purpose the segregation of laying from non-laying hens.

The object of my invention is to provide a simple and inexpensive device composed of few parts, which is easy to manufacture and 15 is readily assembled and installed.

I attain my object by combining with a wall, or the like, having an opening therein and separating an enclosure from an adjacent open space, an enclosed nest having an 20 opening adapted for registration with said wall opening, operable means normally supporting said nest with its opening in registration with said wall opening, said means being adapted to sustain the weight of the 25 nest without effect, but to partially rotate said nest slowly under additional weight thereby to place the opening of said nest out of registration with said wall opening and instead exposing the opening of the nest to 30 said enclosure only.

My object in restraining the operating of the rotation of my enclosed nest is to prevent scaring the hen off the nest by a sudden movement of the latter.

My invention may be practically carried 35 out in the manner illustrated in the accompanying drawings, in which:

Fig. 1 is a side elevation partly in section, showing a fence provided with an opening 40 and to which fence my segregating nest is affixed, this figure showing the normal positions of the co-operating parts of my segregating nest.

Fig. 2 is a view similar to Fig. 1, but in 45 this instance my segregating nest has been rotated so as to place the opening thereof out of registration with the opening in the wall so that the hen will be confined in the space enclosed by the latter;

Fig. 3 is a plan section on the line 3—3 of Fig. 2;

Fig. 4 is a sectional detail of the pivotal support for the nest, the section being taken on the line 4—4 of Fig. 1; and

Fig. 5 is a sectional detail of the cylinder and pump element of my segregating nest

by which the sudden movement of the latter is restrained.

a represents a fence which may consist of rails *a'* and wire netting portions *b*, as illustrated in Figs. 1 and 2. The wall is provided with an opening *c* and the enclosed nest *d* is provided with a single opening *e* which normally registers with the opening *c* in the wall. Directly above the opening *c* in 60 the wall is affixed a bracket *f* and on the bracket is pivoted a lever arm *g*, the free end of which is yieldingly supported by a spring *h*. Devices are provided on said arm by which the tension of the spring *h* may be 65 adjusted. These devices consist of a slot *g'* in the arm over which a clip *h'* is mounted. Said clip *h'* is provided with a clamping screw *h*² which passes through the slot *g'* in the arm. A thumb nut *h*³ is provided on 70 said clamping screw to fasten the clip to the arm when the spring is adjusted to the correct tension.

A rod *i* supporting the nest *d*, is carried by a fitting *j* on the arm *g*. Said fitting 75 consists of a member *j'* which is pivotally supported to the arm. A hook *j*² swivels in said member *j'* and passes through an eye in the rod *i*. Said rod *i* has a twisted spiral portion *i'* which bears in a slotted aperture 80 *k* formed by a clip *k'* fastened to and forming a part of the bracket *f*. The twist in said rod *i* thus causes said rod to be rotated when the rod is moved vertically. The downward movement of the rod will cause 85 the partial rotation thereof and therewith of the nest in one direction and the return, upward, vertical movement will cause its rotation in the reverse direction. The nest *d* is suspended from the pendent rod *i* and the 90 spring *h* is adjusted so as to exactly support the weight of the nest and to hold the latter so positioned that its opening *e* will register with the opening *c* in the wall *a*.

In order to prevent the sudden movement 100 of the parts when a hen sets upon a nest I provide a cylinder *l* filled with a fluid and provided with a piston *m* which reciprocates therein. The piston rod thereof extends through said piston *m* and is hollow for a 105 portion of its length. An orifice *o* extends through the wall of said piston rod above the piston and is proportioned relatively to the interval of time it shall take the movement of the piston to displace the fluid in 110 the cylinder from one end to the other of the latter. The piston rod *n* is connected

with the lever arm *g* through a bifurcated fitting *p* which is pivotally connected thereto.

In order to maintain the nest in vertical alignment at all times, I provide a bracket *q* below the opening in the wall and provide on the bottom of the nest *d* a rod *r* which is journaled in the bracket *q* and also slides therein.

10 The operation of my device is self evident from its description: When a hen enters the nest *d* and settles down to lay, thus remaining in the nest some considerable time, the weight of the hen will cause the 15 said operating device slowly to rotate the nest until the opening *e* thereof is placed out of registration with the opening in the fence and permits the hen to leave the nest only in the space enclosed by said fence. As 20 soon as the hen has left the nest the latter will assume its normal position. As mentioned, the movement of the nest is restrained to be so gradual as to not frighten the hen. The slow movement of the nest 25 also permits a non-laying fowl that has entered the nest, to leave it again if remaining in the nest only a short time.

I claim:

1. In a device of the character described, a 30 bracket, a lever-arm mounted thereon, means connected to said lever-arm adapting the latter to sustain a predetermined weight, a vertically movable rod pendent from said lever-arm, means for causing the partial ro-

tation of said pendent rod during its vertical movement, an enclosed nest suspended from said rod, said nest provided with an opening, means restraining the sudden movement of said lever-arm, whereby additional weight imposed upon said nest will cause its partial rotation and thus relatively move its opening from one position to another, slowly.

2. Claim 1 distinguished in that said restraining means of the lever-arm consists of a cylinder filled with a fluid and a plunger therein provided with an orifice and operable to displace said fluid from one end of the cylinder to the other.

3. In a device of the character described, 50 a bracket, a lever-arm mounted thereon, means connected to said lever arm adapting the latter to sustain a predetermined weight, a rod pendent from said lever arm, means for causing the partial rotation of said rod 55 during its vertical movement, an enclosed nest suspended from said pendent rod, said nest provided with an opening, and means restraining the sudden movement of said lever-arm, such means consisting of a cylinder filled with a fluid and plunger therein provided with an orifice and operable to displace said fluid from one end of the cylinder to the other, whereby a weight imposed upon said nest will cause its partial rotation 60 and thus relatively move its opening from one position to the other at a slow speed.

JOHN A. MOORE.
